Primary Examiner — Richard Kearney*Assistant Examiner* — Kendra L Hebel(74) *Attorney, Agent, or Firm* — Mitchell Law PLLC;
Matthew W. Mitchell(57) **CLAIM**

The ornamental design for a combination knife and scale as shown and described.

DESCRIPTION

FIG. 1 is a front, left-side, top perspective view showing my new design;
FIG. 2 is front, left-side, bottom perspective view thereof;

FIG. 3 is front, right-side, top perspective view thereof;

FIG. 4 is front, right-side, bottom perspective view thereof;

FIG. 5 is a front view thereof;

FIG. 6 is a top plan view thereof;

FIG. 7 is a bottom plan view thereof;

FIG. 8 is a left-side view thereof; and,

FIG. 9 is a right-side view thereof.

The broken lines in the figures show portions of the combination knife and scale that form no part of the claimed design.

1 Claim, 9 Drawing Sheets(56)
